CLAIM

The ornamental design for a vehicle wheel cover, as shown and described.

DESCRIPTION

FIG. 1 is a front elevational view of a vehicle wheel cover showing the claimed design; and,

FIG. 2 is a front perspective view of the vehicle wheel cover. The dashed broken lines represent boundaries of the design; the dashed broken lines themselves and the areas within form no part of the claimed design.

1 Claim, 2 Drawing Sheets

FIG. 1

FIG. 2
